UNITED STATES PATENT OFFICE.

DAVID R. BONE, OF OGLESBY, TEXAS.

APPARATUS FOR HYDRATING LIME.

Application filed August 13, 1921. Serial No. 491,908.

To all whom it may concern:

Be it known that I, DAVID R. BONE, a citizen of the United States of America, residing at Oglesby, in the county of Coryell 5 and State of Texas, have invented certain new and useful Improvements in an Apparatus for Hydrating Lime, of which the following is a specification.

My invention relates to an apparatus for 10 producing hydrated lime; and the object is to combine the means that are required and necessary in making a high grade hydrated lime; to provide a new and improved combination of apparatus for making hydrated 15 lime whereby it may be burned and hydrated in a simple and economical manner and by the means of which a much purer lime can be made with much less expense; and by dispensing with much of the machinery 20 heretofore used in hydrating lime. Other objects and advantages will be fully explained in the following description and the invention will be more particularly 25 pointed out in the claim.

Reference is had to the accompanying drawings which form a part of this application.

Fig. 1 is a diagrammatic view, showing a 30 hydrating lime plant. Fig. 2 is a vertical section of the lime elevating mechanism with a perspective view of a screen and bagging machine. Fig. 3 is a detail view of the car lowering and elevating means.

Similar characters of reference are used 35 to indicate the same parts throughout the several views.

In carrying out the improved invention herein set forth, I use the heat producing devices shown in the patent granted to me 40 on Oct. 15, 1918, No. 1,281,902, for burning lime. These devices include a kiln 1 for burning the lime, a furnace 4 for burning fuel which is fed thereto by stoking devices 16, 18, and 23. The furnace 4 is provided 45 with a grate 5, and fuel 14 falls through the fire zone 15 on the grate 5. The combustion is aided by heated air which comes from a fire box 10. This fire box is provided with grate bars 12, doors 11 and 13, a damper or valve 50 24, flue 8, and a funnel-shaped discharge 9. The heated air rises from box 10 up through the fuel 14. The fuel is thoroughly consumed in the furnace 4 which produces great heat. The heat is directed to the lime kiln 55 or lime burning furnace 1 into which the lime in the raw state is fed. The furnace 4

is duplicated with all its working parts as shown on both sides of the kiln. After the lime is burned thoroughly, it passes down through the discharge hopper or outlet 25' 60 which is provided with gates or slides 26 so that the burned lime can be dumped into small tram cars 27. Tracks 28 are provided for the tram cars 27. The tram cars are used to carry the lime to a dipping vat 29. 65 Track sections 28' which are aligned with the tracks 28 are provided. A car is filled approximately one-third full of lime from hopper or discharge chute 25' and runs on the tracks 28 and track sections 28'. While 70 the car is standing on the sections 28', suitable lowering and elevating means are used to let the car with the lime therein down into the water in vat 29. The car is left in the water in vat 29 long enough to wet the 75 lime thoroughly, approximately one minute is sufficient time. The lime is lowered into the water while the lime is hot. The car is not water tight and the water readily enters the car and penetrates the lime. After 80 the car has remained in the water a sufficient length of time, the car is elevated and run onto tracks 30 and then switched to storage track-portion 31. The dipping of the cars into the water (the water constantly flowing 85 into and out of the vat) causes or permits the lime to absorb water and the lime then fills the cars entirely by expansion. The expansion of the hydrating lime, in the bulk confined in each car or walled container, 90 fills the interstices between the lumps and disintegrating portions of lime while the walls of the container prevent lateral expansion of the bulk and at the same time exclude air from the upright sides of the 95 bulk. These walls also prevent escape of the resultant gas through the lateral or upright sides of the bulk, so that these gases and the steam are detained in the bulk for 100 assisting in its hydration. Since the bulk can not spread laterally or downwardly, it rises to approximately three times its original height, thus increasing the pressure upon parts of the bulk below its upper surface. The lime which first hydrates, being lighter 105 than the lumps, is forced to the top of the bulk, and this aids the container in excluding air from the inner parts of the bulk. Therefore, much of the resultant gas is not 110 only detained in the bulk, but permanently retained therein, thus not only assisting the hydrating process, but conserving the vol...

able chemical elements which tend to pass off and be lost in the atmosphere. The cars of watered lime are left on the storage track-portion 31 about twenty-four hours for giving time for finishing the hydration, enough tram cars are provided for this purpose, the tracks 31 being long enough to accommodate the necessary number of cars.

After the hydration is completed, one car 10 at a time is run from track-portion 31 over switch tracks 32 back to tracks 30 and then on a tipple 33 so that the contents of the car can be dumped into an elevator bin 34. This bin is enlarged towards the bottom which 15 is projected down into the ground. The lime is elevated by buckets 35 which are attached to a traveling belt 36 which runs on pulleys 37 and 38. The lime is thrown from the buckets 35 down a chute 39 into a screen 40. By this system the hydrated lime is separated from all the cores and the impurities and from everything that is not lime and a perfectly pure hydrate is all that remains after the screening operation. The pure 25 lime is delivered from the screen 40 into a bin 41 and the lime is taken from the bin 41 into a bagging machine 42 where the lime is sacked and pressed for commercial uses. The impurities will be stopped by the screen 30 and can be removed and thrown out into waste receptacles.

The result of such system is the production of a high grade lime having a high de-

gree of purity. It may require more time for hydration than other systems in use, but 35 the time can be compensated for by using a sufficient number of cars so that the volume of lime made will be as great in proportion as by other systems and the system can be carried out with a small amount of labor. 40

By this system the hydrate is separated from all the cores and the impurities and from everything that is not lime and a perfectly pure hydrate is all that remains after 45 it is separated.

Various changes in the sizes, proportions, construction and arrangement of the several parts of the apparatus for carrying out the hydration of the lime may be made without departing from my invention. 50

What I claim, is,—

The apparatus for obtaining kilned hydrated lime, including a lime kiln provided with an outlet for expelling the kilned lime, a car-track extending under the outlet and including a section capable of being raised and lowered, cars on the car-track for receiving lime from the said outlet and carrying it to said section, and a body of water in position relative to said section to receive and immerse the cars of kilned lime, for the purpose specified. 55 60

In testimony whereof, I set my hand August 10th, 1921.

DAVID R. BONE.
